J. P. MARSHALL,
REPAIR JACK STAND,
APPLICATION FILED MAR. 29, 1920.

1,350,555.

Patented Aug. 24, 1920.

FIG. 1.

FIG. 2.

Inventor
J.P. Marshall.

By *Paul D. Wright* Attorney

UNITED STATES PATENT OFFICE.

JAMES P. MARSHALL, OF INDIANAPOLIS, INDIANA.

REPAIR JACK-STAND.

1,350,555.

Specification of Letters Patent. Patented Aug. 24, 1920.

Application filed March 29, 1920. Serial No. 369,690.

To all whom it may concern:

Be it known that I, JAMES P. MARSHALL, a citizen of the United States, residing at Indianapolis, in the county of Marion and

5 State of Indiana, have invented certain new and useful Improvements in Repair Jack-Stands, of which the following is a specification, reference being had therein to the accompanying drawing.

10 This invention relates to certain new and useful improvements in jack stands, the object being to provide a repair jack stand with a heel puller which will remove quickly as many heel lifts as desired in repairing the 15 heel by simply operating a lever.

Another object of my invention is to provide a repair jack stand which is exceedingly simple and cheap in construction, the same being provided with a socket at its upper end 20 to receive the spindle of a last which is provided with a straight back to prevent the same from tearing the lining of the shoe when the shoe is being removed.

Other and further objects and advantages 25 of the invention will be hereinafter set forth and the novel features thereof defined by the appended claim.

In the drawings,

Figure 1 is a side elevation of a jack stand 30 constructed in accordance with my invention; and

Fig. 2 is a section taken on line 2—2 of Fig. 1.

In carrying out my invention I employ a 35 circular base 1 on which is mounted a standard 2 secured in position thereon by rivets or bolts 3, said standard being preferably formed the shape of a cross in cross section having a circular base 4 which is arranged 40 on the circular base 1 and secured as clearly shown.

The upper end of the standard 2 terminates in a rounded portion 5 having a socket 6 adapted to receive the spindle 7 of a last 8 45 which is provided with a straight back as shown at 9 for preventing the last from tearing the lining of the shoe when the shoe is being inserted or removed therefrom. The spindle is movably mounted within the 50 socket in order to allow the last to be turned

to any position desired and is locked in adjusted position by thumb bolt 10 working in a threaded bore in the rounded portion 5 and engaging the spindle.

One of the arms of the cross-shaped standard 2 is extended as shown at 11 to form a support which is provided with a notch 12 for the purpose hereinafter fully described. Said arm is also provided with bearings 13 and 14 in which is mounted a pointed punch 15 capable of moving up and down in the bearings, the point extending into the notch 12 of the support 11. The punch 15 is notched as shown at 16 into which extends a lever 17 pivotally mounted on the standard 2 as shown at 18 by means of which the punch is moved up and down and by placing a heel of a shoe on the support 11 when the punch is raised by forcing downwardly on the punch the lifts of the heel can be removed 70 from the shoe quickly as the punch is forced between the lifts so as to force the outer lifts off the heel of the shoe as the lever is depressed.

From the foregoing description it will be 75 seen that I have provided a repair jack stand having a socket at its upper end to receive the spindle of a last in order to allow the last to be adjusted into any position desired in connection with a heel puller comprising 80 a punch operated by a lever.

What I claim is:—

A jack stand having a standard substantially cross-shaped in cross section, one of the arms being provided with an extension 85 having a notch, said arm being provided with bearings, a punch slidably mounted in said bearings having a notch and a lever pivotally mounted on said standard working in the notch of said punch for reciprocating said 90 punch toward and from the notch in the extension.

In testimony whereof I have hereunto affixed my signature in the presence of two witnesses.

JAMES P. MARSHALL.

Witnesses:

PAUL MARSHALL,
CARL D. FURREE.
